UNITED STATES PATENT OFFICE.

LEMUEL B. STEVENS, OF LOGANSPORT, INDIANA.

MILKING-MACHINE.

No. 840,969.

Specification of Letters Patent.

Patented Jan. 8, 1907.

Application filed June 25, 1906. Serial No. 323,240.

To all whom it may concern:

Be it known that I, LEMUEL B. STEVENS, a citizen of the United States, and a resident of Logansport, in the county of Cass and State of Indiana, have invented a new and Improved Milking-Machine, of which the following is a full, clear, and exact description.

This invention relates to improvements in machines for milking cows, the object being to provide a device for this purpose that will be simple in construction, inexpensive, and easily operated.

I will describe a milking-machine embodying my invention and then point out the novel features in the appended claims.

Reference is to be had to the accompanying drawings, forming a part of this specification, in which similar characters of reference indicate corresponding parts in all the figures.

Figure 1 is an elevation, partly in section, of a milking-machine embodying my invention. Fig. 2 is a plan thereof, and Fig. 3 is sectional detail showing an adjusting mechanism employed.

In carrying out my invention I employ a pump comprising a cylinder 1, in which a piston 2 operates, the said piston having an opening which is closed on the downward movement of the piston by means of a valve 3, here shown as a flap-valve. The stem 4 of the piston extends downward through the bottom wall of the cylinder and connects with a lever 5, pivotally connected to a hanger 6, attached to the pump-cylinder. The cylinder is supported by means of a rod 7, adjustable vertically in a tubular support 8, designed to engage with the ground or floor. The rod 7 is provided with a plurality of notches 9, in any one of which a pawl 10 may engage for holding the pump as adjusted vertically. This pawl 10 is movable through a slot 11 in the tubular support and is pivoted to a bracket 12, secured to said tubular support.

The tubular support 8 has a swinging connection in a substantially horizontal plane with a seat 13. As here shown, this connection consists of a rod or tube 14, attached to a coupling 15 on the part 8 and also attached to a T-fitting 16, having swinging connection with the forward portion of the seat and with a hanger 17, attached to the seat. By this means the pump and the parts carried thereby may be swung laterally with relation to the seat.

Communicating with the upper portion of the cylinder 1 are branch pipes 18, and each branch pipe has a flexible tube or pipe connection 19 with a teat-receiver 20, made in the form of a cup and preferably of flexible material.

Communicating with the lower portion of the pump-cylinder is a discharge-tube 21, of rubber or like flexible material, for conducting the milk to a pail or bucket, (indicated by the dotted lines 22 in Fig. 1,) the said pail or bucket being supported on a shelf 23, attached to the legs of the stool or seat.

In the operation a person sitting on the seat or stool by moving the lever 5 downward will obviously cause a downward movement of the piston, and as the valves carried thereby will be closed the milk will be drawn from the udder, and then upon an upward movement of the piston the valve will open, permitting the milk to pass to the under side of the piston, and then by a subsequent downward movement the milk underneath the piston will be forced through the pipe 21 and at the same time a fresh supply of milk will be drawn.

Having thus described my invention, I claim as new and desire to secure by Letters Patent—

1. A milking-machine comprising a pump, teat-cups communicating with the upper portion thereof, a lever for operating the pump-piston, a vertically-adjustable support for the pump, a stool with which said support has connection, and a discharge-pipe leading from the lower portion of the pump-cylinder.

2. A milking-machine comprising a pump, cups having flexible tube connection with the upper portion of the pump-cylinder, a lever for operating the pump-piston, a support for the pump, consisting of a tubular member, and a toothed rod movable in the tubular member, a pawl pivoted to the tubular member and adapted to engage with any one of the teeth, a rod having connection with said tubular member, a seat with which the rod has swinging connection, and a discharge-tube leading from the lower portion of the pump.

3. A milking-machine comprising a pump-cylinder, a piston for operating in the cylinder, and having an opening, a valve for said opening, teat-cups having flexible tube connection with the upper portion of the pump-cylinder, a stem extended downward from

the piston through the bottom wall of the cylinder, a lever with which said stem connects, a support for the pump, a seat, a connection between the support and seat, a shelf attached to the legs of the seat, and a discharge-tube leading from the lower portion of the pump-cylinder.

In testimony whereof I have signed my name to this specification in the presence of two subscribing witnesses.

LEMUEL B. STEVENS.
